Primary Examiner — Anhdao Doan*(74) Attorney, Agent, or Firm* — Perry + Currier Inc.(57) **CLAIM**

We claim the ornamental design for a tube isotropic diffusion phantom, as shown and described.

DESCRIPTION

FIG. 1 is a front perspective view of a tube isotropic diffusion phantom;

FIG. 2 is a front elevational view thereof;

FIG. 3 is a right elevational view thereof;

FIG. 4 is a top plan view thereof;

FIG. 5 is a bottom plan view thereof;

FIG. 6 is a cutout of a right elevational view thereof within a Falcon tube;

FIG. 7 is a cutout of a front perspective view thereof within a Falcon tube; and,

FIG. 8 is a exploded front perspective view thereof and a Falcon tube.

In the drawings, the broken lines depict environmental subject matter only and form no part of the claimed design.
